UNITED STATES PATENT OFFICE.

ROBERT MUNRO, OF JOHNSTOWN, PENNSYLVANIA.

SHIELD FOR RADIATORS.

1,176,087.

Specification of Letters Patent. Patented Mar. 21, 1916.

Application filed June 8, 1912. Serial No. 702,475.

To all whom it may concern:

Be it known that I, ROBERT MUNRO, a citizen of the United States, residing at Johnstown, in the county of Cambria and State 5 of Pennsylvania, have invented a new and useful Improvements in Shields for Radiators, of which improvement the following is a specification.

My invention relates to shields for radiators. Heretofore, so far as I am aware, shields of this character have been secured upon or affixed to the radiator, requiring, when it is necessary to remove the shield, to sever the connection between the shield 15 and the radiator.

The object of the present invention is to produce a shield that may be securely but removably supported between the wall and the radiator so as to protect the wall against 20 the heat of the radiator. I accomplish this object by means of the device hereinafter more specifically described, reference being had to the accompanying drawings, forming part hereof, in which—

25 Figure 1 is a front elevation of the shield. Fig. 2 is an elevation of the opposite side of the shield. Fig. 3 is an end view of one of the shields, showing the position assumed by the same when applied to a radiator, portions being broken away and shown in section to more clearly illustrate the invention.

Referring to said drawings, 1 is a shield adapted to be interposed between the radiator and the wall to protect the wall against 35 the heat of the radiator and the shield comprises the body portion A, side pieces B and at the upper end the hood piece C which is adapted to pass over and inclose the top of the radiator. Secured upon the sides of the 40 body portion are a number of blade springs 2, 2 and 3, 3, the said blade springs being secured to both sides of the body portion substantially opposite to each other, and being, respectively, connected by the cross bars 45 4 and 5 which serve to hold the spring

blades 2, 2 and 3, 3 against swinging out of a substantially parallel relation to themselves and the side edges of the shield. The resiliency of the opposed spring blades 2, 2 and 3, 3 upon opposite sides of the shield 50 causes them to engage the wall of the room and the radiator, respectively, so as to hold the shield yieldably against accidental displacement. The bars 4 and 5 do not necessarily engage directly with either the wall 55 or the radiator, although they may do so under some conditions. The shield is thus held yieldably in position between the radiator and the wall so as to protect the wall against the heat from the radiator, although 60 the shield can be readily removed at any time when such may become desirable by merely applying a sufficient amount of force thereto to overcome the action of the spring blades 2, 2 and 3, 3. The springs in contact with the wall may be covered with 65 cloth, or other suitable material, to protect the wall.

Having described my invention, what I claim and desire to secure by Letters Patent is:

A shield for protecting walls against the heat of radiators, including a guard plate adapted to be interposed between the wall and the radiator, opposed sets of spring 75 blades mounted upon opposite sides of the guard plate for yieldably and frictionally engaging the wall and radiator respectively to hold the guard plate removably in an intermediate position between the radiator and 80 the wall, and bars connecting the spring blades of each set to retain the same in proper relative position.

In testimony whereof, I have hereunto signed by name in the presence of two subscribing witnesses.

ROBERT MUNRO.

In the presence of—

FRANCIS B. HAMILTON,
J. D. W. SNOWDEN.
